COMBINED BOTTLE HOLDER AND FINGER SUPPORT

Caralee M. Shirley and Alton L. Shirley, both of 57 Hollybrook Terrace, Cranston, R.I.

Filed Apr. 30, 1962, Ser. No. 69,900

Term of patent 14 years

(Cl. D86—10)

FIG. 1

FIG. 3

FIG. 4

FIG. 1 is a perspective view of a combined bottle holder and finger support showing our design;
FIG. 2 is a top plan view thereof;
FIG. 3 is a side elevational view thereof; and
FIG. 4 is a bottom view thereof.

We claim:

The ornamental design for a combined bottle holder and finger support, substantially as shown.
